UNITED STATES PATENT OFFICE.

WILLIAM T. BENNETT, JR., OF COPE, COLORADO.

FENCE-POST BASE.

1,284,763.

Specification of Letters Patent.

Patented Nov. 12, 1918.

Application filed September 29, 1917. Serial No. 193,971.

To all whom it may concern:

Be it known that I, WILLIAM T. BENNETT, Jr., a citizen of the United States, and a resident of Cope, in the county of Washington and State of Colorado, have invented a new and Improved Fence-Post Base, of which the following is a full, clear, and exact description.

My invention relates to tubular bases or 10 sockets for receiving a fence post or the like, and more particularly is intended for embodiment in reinforced concrete bases.

The prime object of the invention is to provide a fence post base of such a form 15 as to drain and be afforded ventilation whereby to prevent accumulation of moisture that would result in the rotting of the post.

A further object of the invention is to 20 provide means whereby to firmly secure the post in the base with facility and despatch.

Reference is to be had to the accompanying drawings forming a part of this specification in which similar reference characters indicate corresponding parts in all 25 the views.

Figure 1 is a transverse vertical section of a post base embodying my invention showing a portion of a fence post;

30 Fig. 2 is a view similar to Fig. 1 but taken at right angles thereto, the post being omitted;

Fig. 3 is a horizontal section on the line 35 3-3, Fig. 1;

Fig. 4 is a perspective view of a wedge employed.

Fig. 5 is a plan view of the cover that may be employed on my improved base.

In carrying out my invention in practice, 40 I produce a tubular shell designated generally by the numeral 10 forming the same of reinforced concrete, there being indicated annular reinforcing wires 11 at various heights in the shell. The said shell is formed with a throughbore and is tapering whereby to flare upwardly.

On the shell 10 at the interior I produce, 45 at one side thereof a pair of vertical ribs 12, said ribs being curved transversely to form approximately to the external surface of a post A.

Diametrically opposite the ribs 12, I provide a horizontal set screw 13 which engages a nut 14 which is received between vertical 50 ribs 15 so that the nut is prevented from turning. The set screw is adapted to bind

against the post A to give it a firm bearing against the ribs 12. With the described arrangement it will be seen that when the post is in position, spaces 16 will be formed 50 for the drainage of water and circulation of air, whereby to permit quick drying of the post. Also, between the spaced ribs 12 an additional vertical channel 16a is produced, whereby to reduce the surface liable 55 to retain moisture. The spacing of the ribs 12 by the said channel furthermore promotes the firm holding of the post by reason of having two separated vertical zones or areas of contact, the two distinct bearings 70 being more effective in rigidly holding the post than would a single bearing of equal width against which the post might take a bearing along a single, approximately vertical line, thereby leaving the post unsteady. 75 The spaces 16 are adapted to accommodate reinforced cement wedges 17 to each of which a wire 18 is connected and having an eye 19 or other device to constitute a finger hold. The wedges are dropped into the 80 spaces 16 one at each side of the set screw 13 and by forcing the wedges in place the post is held with additional security, the wedges thus coacting with the ribs 12 and not materially affecting the ventilation. 85

When the base is employed in sandy grounds where the wind is liable to cause the base to be filled with sand, I prefer to employ a cover 20 which may be made in segments the adjacent ends of which are fastened in any suitable manner to vary the size of the central opening to suit the particular post. In the present example each segment is formed at one end with bendable tongues 21 and at the opposite end with holes 22 95 formed at different distances from the end of the segment so that the tongues may be entered in holes 22 more or less distant from the end and bent over as indicated in Fig. 5 to adjust the size of the cover to a particular 100 post A. As seen clearly in Fig. 1 the cover is conical to shed the sand, etc., blown against the same.

I wish to state in conclusion that although the illustrated example constitutes a practical embodiment of my invention, I do not limit myself strictly to the mechanical details herein illustrated, since manifestly the same can be considerably varied without departure from the spirit of the invention as defined in the appended claims.

Having thus described my invention, I

claim as new, and desire to secure by Letters Patent:—

1. A base for fence posts or the like including a tubular shell having a throughbore to receive the post, the said shell having laterally spaced vertical fixed ribs on the interior at one side thereof, against which the post may take a bearing, said ribs extending approximately the full height of the shell and adjustable means on the shell at the opposite side from the ribs and adapted to exert pressure against the post in the direction of the said ribs, said ribs serving to form with the post an air space around the post between the same and the shell.
2. A base for fence posts including a shell, having spaced vertical ribs at a side thereof at the interior of the shell and extending approximately the full height of the shell, ribs on the post diametrically opposite the first ribs and extending from approximately the top of the shell downwardly a short dis-
3. A base for fence posts or the like including a tubular shell having an upwardly flaring throughbore to receive the post, the said shell having spaced vertical ribs on the interior at one side thereof, against which the post may take a bearing, and means on the shell at the opposite side adapted to exert pressure against the post in the direction of the said ribs, said ribs serving to form with the post an air space around the post between the same and the shell, together with wedge means adapted to bear against the post and shell at the side of the post opposite the said ribs at each side of the first mentioned means.

WILLIAM T. BENNETT, JR.
